TRAY FOR A WRAPPED FRUIT CONTAINER

Joseph E. Murphy, Hicksville, and Murray Schnall, Brooklyn, N. Y., assignors to See-Qual Package Corp., New York, N. Y., a corporation of New York

Application May 5, 1953, Serial No. 24,862

Term of patent 14 years

(Cl. D44—10)

To all whom it may concern:

Be it known that we, Joseph E. Murphy and Murray Schnall, both citizens of the United States, residents of Hicksville, Nassau County, State of New York, and Brooklyn, Kings County, State of New York, respectively, have invented a new, original and ornamental Design for a Tray for a Wrapped Fruit Container, of which the following is a specification, reference being had to the accompanying drawing, forming part hereof.

In the drawing,

Figures 4 and 5 are sections taken, respectively, along lines 4—4 and 5—5 of Figure 1.

We claim:

The ornamental design for a tray for a wrapped fruit container, substantially as shown.

JOSEPH E. MURPHY.
MURRAY SCHNALL.
